(57) **CLAIM**

We claim the ornamental design for a jar attachment for a
blender assembly, as shown and described.

DESCRIPTION

FIG. 1 is a front top perspective view illustrating a jar
attachment for a blender assembly of the present disclosure;
FIG. 2 is a rear top perspective view of the jar attachment for
a blender assembly of FIG. 1;

FIG. 3 is a front elevational view of the jar attachment for
a blender assembly of FIG. 1;

FIG. 4 is a rear elevational view of the jar attachment for a
blender assembly of FIG. 1;

FIG. 5 is a first side elevational view of the jar attachment
for a blender assembly of FIG. 1;

FIG. 6 is a second side elevational view of the jar attachment
for a blender assembly of FIG. 1;

FIG. 7 is a top plan view of the jar attachment for a blender
assembly of FIG. 1;

FIG. 8 is a bottom plan view of the jar attachment for a
blender assembly of FIG. 1;

FIG. 9 is a front top perspective view illustrating a jar
attachment for a blender assembly of the present disclosure;
FIG. 10 is a rear top perspective view of the jar attachment
for a blender assembly of FIG. 9;

FIG. 11 is a front elevational view of the jar attachment for
a blender assembly of FIG. 9;

FIG. 12 is a rear elevational view of the jar attachment for
a blender assembly of FIG. 9;

FIG. 13 is a first side elevational view of the jar attachment
for a blender assembly of FIG. 9;

FIG. 14 is a second side elevational view of the jar attachment
for a blender assembly of FIG. 9;

FIG. 15 is a top plan view of the jar attachment for a blender
assembly of FIG. 9; and,

FIG. 16 is a bottom plan view of the jar attachment for a
blender assembly of FIG. 9.

The broken lines depict portions of the article that form no
part of the claimed design.
